UNITED STATES PATENT OFFICE.

ABONDIUS CHAPDELAINE, OF NICOLET, QUEBEC, CANADA.

SHOE-FASTENING.

SPECIFICATION forming part of Letters Patent No. 425,301, dated April 8, 1890.

Application filed December 6, 1888. Serial No. 292,864. (No model.)

To all whom it may concern:

Be it known that I, ABONDIUS CHAPDELAINE, a citizen of Canada, residing at Nicolet, in the county of Nicolet, Province of Quebec, Canada, have invented certain new and useful Improvements in Boot-Clasps; and I do hereby declare that the following is a full, clear, and exact description of the invention, which will enable others skilled in the art to 5 which it appertains to make and use the same.

My invention relates to fastenings for boots and shoes in which the upper is slit downward in front or at the side of the instep.

My object in this invention is to provide a 15 convenient and secure fastening that will be completely hidden from view, leaving the outer surface of the boot free from all such projecting fastenings as buttons, laces, or outside hooks, all of which have at least the objection of being injurious to clothing that 20 may be in continuous or frequent contact with them.

To this end my improved clasp consists in a hooking device, one part of which is secured 25 to the underlap side of the upper, while the other part is attached to the under side of the overlap side, as hereinafter more fully described, reference being had to the accompanying drawings, in which—

30 Figure 1 shows detached face views of both parts of the clasp. Fig. 2 shows a longitudinal sectional view of the above, but with the two parts of the clasp closed together. Fig. 3 shows a boot having my improved clasp, the overlap of the boot being opened back. Fig. 4 shows the boot closed up.

A holding-piece composed of the two H-shaped pieces A and B is secured by rivets, or otherwise, to the underlap side H of the 35 boot-upper. The two parts A and B are interlocked together, as shown, to form the holding-piece, and are provided with rivet-holes a' to receive the rivets b', by which the holding-

piece is secured to the boot. A hook-piece C is secured by rivets d' to the overlap I of the 45 boot. The body of this piece is reduced in width by the shoulders e' to the width of the tongue f', which is somewhat less than the distance between the side strips of the piece A. The end of the tongue f' is thinned down 50 to a comparatively sharp edge, so that it may be easily shoved under the cross-bar g' of the piece A.

It will be observed that a certain amount of flexibility is needed in the different parts 55 of this clasp, and on this account the clasp is made preferably of spring-steel, although several other materials might be found equally serviceable.

What I claim as my invention, and desire 60 to secure by Letters Patent, is—

1. A shoe fastening or clasp comprising the two separable members adapted to be secured, respectively, to the overlap and underlap of the shoe, one of said members composed of the 65 complementary parts A and B, placed one upon the other and interlocked, as shown, to leave a space between them, and the other member formed with the tongue constructed to enter the space between the parts A and B 70 and to be held frictionally therein by the said parts, substantially as described.

2. A shoe fastening or clasp composed of the H-shaped pieces A and B, locked together and secured to the underlap of a shoe, and a 75 hook-piece C, having tongue f' to take under the cross-bar g' of the holding-piece, and secured to the overlap of the shoe, substantially as described.

Signed at Nicolet this 20th day of November, 80 1888.

ABONDIUS CHAPDELAINE.

In presence of—

VILMER GENEST,
L. C. AMÉDÉ PRINCE.
